UNITED STATES PATENT OFFICE.

ROY L. DE CAMP, OF LOS ANGELES, CALIFORNIA, ASSIGNOR TO BAKER IRON WORKS, OF LOS ANGELES, CALIFORNIA, A CORPORATION OF CALIFORNIA.

SAFETY DOOR INTERLOCKING SWITCH.

Original application filed September 25, 1917, Serial No. 193,188. Divided and this application filed May 3, 1919. Serial No. 294,429.

To all whom it may concern:

Be it known that I, ROY L. DE CAMP, a citizen of the United States, residing at Los Angeles, in the county of Los Angeles and 5 State of California, have invented a new and useful Safety Door Interlocking Switch, of which the following is a specification.

This invention pertains to switches of the type adapted to be operated by closing and 10 opening movements of a closure or other member, and an object of the invention is to produce a device of this character of minimum liability to become disorganized and one which requires minimum attention to 15 maintain in operative condition.

Another object is to so construct the switch that the operating member thereof will interlock with a member mounted on a door.

20 Another object is to provide a construction in which the switch parts will not be subjected to blows or shocks when the door with which it is used is opened and closed.

This invention is a division of my Patent 25 No. 1,356,698, dated October 26, 1920.

Other objects and advantages will appear in the subjoined detailed description.

The accompanying drawings illustrate the invention:

30 Figure 1 is a fragmental rear elevation of a door structure with the newly invented switch applied thereto, the door being shown in closed position and the switch being closed.

35 Fig. 2 is a plan view of Fig. 1, the door casing being shown in section.

Fig. 3 is a side elevation of the switch, the cover and switch arm being omitted to expose to view the internal mechanism of 40 the switch, the switch being turned 90° clockwise from the position shown in Fig. 1, and the switch being open.

Fig. 4 is an elevation mainly in section on line indicated by x^4-x^4 , Fig. 3.

45 Fig. 5 is a plan section on line indicated by x^5-x^5 , Fig. 3.

The invention is designed to be used in connection with any suitable closure, or other movable member, and is especially useful in connection with elevator doors, an elevator door being indicated at 1 in Fig. 1. The door 1 is provided with a switch-oper-

ating arm 2 of suitable construction. The operating arm 2 is so constructed as to engage a rotative switch member indicated in 55 general by the character 3. In this instance, the member 3 is provided with teeth 4, 4' adapted to engage a tooth 5 of the arm 2. The arm 2 is attached by screws 6 or their equivalents to the door 1. The teeth 4, 4' 60 project from the hub 7 of the member 3. The hub 7 fits loosely on the outer projecting end of a stud 8 which is tightly inserted in an internal boss 9 of a switch case 10, there being a shoulder 11 on the stud 8 seated 65 against the boss 9. The side of the case 10 opposite the boss 9 is formed by a removable cover 12 fastened in place by screws 13 or equivalents and provided with a central orifice 14 to accommodate the inner end 70 of the hub 7.

The hub 7 rests against the outer face of a drum 15 which is circular excepting as hereinafter noted and which is constructed of any suitable electric-insulating material, the 75 drum 15 being keyed to the hub 7 so as to be rotated by turning of the switch-operating arm. In the instance shown in the drawings the keying of the drum 15 to the hub 7 is accomplished by pins 16 projecting from the hub 7 into sockets 17 formed in the drum 15 as clearly shown in Fig. 5. Thus when the switch-operating arm is turned the hub 7 and drum 15 are rotated on the stud 8. A washer 18 is preferably interposed between 80 the stud shoulder 11 and the drum 15 as shown in Fig. 4 and the washer 19 is placed on the outer end of the stud 8 against the outer face of the hub 7. The washer 19 is held against outward displacement by any 85 suitable means, in the instance shown in the drawings said means comprising a cotter pin 20 inserted through a transverse hole 21 in the stud 8.

The drum 15 is provided on its curved periphery with semi-circular contact members 22, 23 mounted opposite to one another and fastened to the drum by any suitable means such, for instance, as screws 24. The drum 15 is cut away at one side to form a flat face 25 along which extends a connector 26 which may be in the form of a copper strip or equivalent and which has its ends 95 inserted between the drum and the contacts 100

22, 23, two of the screws 24 passing through the ends of the connector 26 to firmly hold it in place.

When the drum 15 is turned sufficiently, the contacts 22, 23 are adapted to be engaged by other contact members 27, 28, each of which comprises a straight portion 29, an inwardly bent portion 30, and an end flange 31 engaged in a transverse groove 32 of an angular bracket 33. There are two brackets 33 and each is fastened by screws or equivalents 34, 35 to an insulating member 36 which in turn is fastened by screws or equivalents 37 to the case 10. The screws 35 project out sufficiently far beyond the inner face of the brackets 33 to form binding posts and on said binding posts are mounted washers 38 having semi-circular outer turned flanges 39. Binding nuts 40 on the screws 35 may be turned up to hold the leads, not shown, by which the switch is electrically connected in the control circuit of the elevator or other circuit to be closed and opened by operation of the switch. Means are provided to yieldingly hold the contacts 27, 28 with their curved portions 30 in engagement with the contacts 22, 23 when the drum is turned sufficiently far for that purpose and such means are constructed as follows, though it is understood that they may be otherwise constructed if desired. The straight portion 29 of each contact member 27, 28 is provided with a perforation 41 to receive a headed pin 42 which projects through a perforation 43 in the bracket 33, the head of the pin being at the outer face of the straight portion 29. Each pin 42 is provided with washers 44 and coil springs 45 between the washers, said washers and springs being held in place by cotter pins 46 passing through holes 47 in the pins 42. The expansive force of the springs 45 pulls the heads of the pins 42 against the contacts 27, 28 so as to force the contact portions 30 toward the drum 15 as is clearly understood.

It is now clear that when either of the contacts 22, 23 are in engagement with the contact 27 electric current will flow between the binding posts 35.

From the foregoing it is clear that the switch is readily assembled and disassembled for, by removing the cotter pin 46, the washer 19, hub 7 and drum 15 may be slipped off of the stud 8, and by removing the cotter pins 46 the pins 42 may be withdrawn from the perforations 41, 43 so as to release the contacts 27, 28.

The hub 7 is provided with an arm 49 which is adapted to engage a stop 50 on the case 10 when the switch is open, said stop being formed by an outwardly projecting lug of a strip 51 that is fastened in place by one of the screws 13, or said stop may be otherwise constructed, if desired. Fas-
65 tened to the arm 49 is a coil spring 52 which

is connected with the case 10 by one of the screws 13. This spring 52 is so arranged as to tend to move the arm 49 into engagement with the stop 50 when the switch is closed.

In practical operation, assuming, for example, that the binding posts 35 are connected in a circuit controlling the operation of an elevator, it is clear that when the elevator door 1 is in the unclosed position the switch will be in open position and thus break the electric circuit, and that in order for the operator to close the circuit so that he can operate the elevator car it will be necessary for him to close the door, as in Fig. 1, so as to move the switch-operating arm 2 sufficiently far to cause engagement of the contact 27 with the contact 22.

As the arm 2 moves to the left in Fig. 1, it is clear that said arm interlocks with the switch-operating member 4 by reason of the teeth 4, 4' engaging the teeth 5. It is also clear that when the door 1 is moved to the left to open it the arm 2, because of its interlocking with the switch-operating member, will open the switch. Thus it is readily seen that opening movement of the switch-operating arm, as well as closing movement thereof, is positively effected by movement of the elevator door and not through the agency of any spring, weights, or by gravity. The spring 52 merely holds the member 3 in such position that the tooth 5 will readily engage the tooth 4' when the door is moved from open to closed position.

The switch-operating member 3 may be turned to a position 90° from that shown in Fig. 1 and for this purpose the drum 15 may be provided with sockets 48 corresponding with and midway between the sockets 17 so that the pins 16 can be inserted in the sockets 48 by first withdrawing the hub 7 from the stud 8 and turning the hub 90° from the position shown in the drawings and then returning the hub in the turned position to insert the pins 16 in the sockets 48. By this construction it is readily seen that the switch case may be placed above or beneath the closure, if such placing be desirable.

The switch parts are shown in the drawings as being assembled in positions suitable for use with a door opening to the left from the inside of the elevator, but by turning the switch case through an angle of 180° , before fastening it in position on the door casing, and fastening the arm 2 to the door so that the path of movement of the arm will be in a plane above the switch member 3 the door may be arranged to open to the right from the inside of the elevator. This will be clear by simply turning Fig. 1 upside down.

In operation, rotation of the drum causes wiping or rubbing engagement of the con-

acts 22, 23, 27, 28 thus cleaning the contacts of any foreign matter inimical to closing of the electric circuit.

It is noted that cutting away of the drum 5 to form the flat face 25 produces an air gap between the contact portion 30 and the drum thus increasing the insulating of the contact portion 30 from the connector 26.

It is understood that the various parts 10 above specifically described may be otherwise constructed within the spirit and scope of the appended claims.

I claim:

1. In combination, a case, an insulating member in the case secured to the wall thereof, angular metal brackets having one leg secured by screws to the inner face of the insulating member, said screws projecting sufficiently beyond the inner face of the 15 brackets to form binding posts, binding nuts on the screws, a drum of insulating material rotatably mounted in the case, means to turn the drum, electric contacts on the periphery of the drum, electric contacts having flanged 20 ends engaging the other legs of the respective brackets, the last named contacts hav-

ing inwardly bent portions adapted to engage the first contacts when the drum is turned, and means yieldingly holding the second contacts toward the drum. 30

2. In combination, a case having a removable cover, means to hold the cover in place, a stud projecting from the inner face of the case through the cover, a drum of insulation material rotatably mounted on the stud, 35 electric contacts on the periphery of the drum, a hub rotatably mounted on the projecting portion of the stud and projecting through the cover and provided with pins detachably engaging the drum, means on the stud to prevent separation of the hub and drum, electric contacts mounted in the case and insulated therefrom, and means yieldingly holding the last contacts toward the drum. 40

Signed at Los Angeles, California, this 45
8th day of April, 1919.

ROY L. DE CAMP.
